UNITED STATES PATENT OFFICE.

JERROLD F. WALTON, OF STURGIS, MICHIGAN.

ADJUSTABLE CHAIR.

1,018,460.

Specification of Letters Patent.

Patented Feb. 27, 1912.

Application filed October 31, 1910. Serial No. 589,885.

To all whom it may concern:

Be it known that I, JERROLD F. WALTON, a citizen of the United States, residing at the city of Sturgis, county of St. Joseph, 5 State of Michigan, have invented certain new and useful Improvements in Adjustable Chairs, of which the following is a specification.

This invention relates to improvements in 10 adjustable chairs.

The main objects of this invention are: First, to provide an improved adjustable chair having an adjustable foot-rest, which, when collapsed, is inconspicuous, the chair 15 having a complete finished appearance. Second, to provide in a chair a collapsible foot-rest structure, adapted also to serve as a rack for books, papers, or the like. Third, to provide in an adjustable chair an 20 improved foot-rest, which is simple and economical in structure, and, at the same time, is very strong and durable and easily adjusted.

Further objects, and objects relating to 25 structural details, will definitely appear from the detailed description to follow.

I accomplish the objects of my invention by the devices and means described in the following specification.

30 The invention is clearly defined and pointed out in the claims.

A structure which is a preferred embodiment of my invention is clearly illustrated in the accompanying drawing, forming a 35 part of this specification, in which:

Figure 1 is an inverted view of a structure embodying the features of my invention. Fig. 2 is a vertical section, taken on a line corresponding to line 2—2 of Fig. 1.

40 Fig. 3 is a vertical section, taken on a line corresponding to line 3—3 of Fig. 1, the foot-rest being extended. Fig. 4 is a detail perspective view with the foot-rest extended. Fig. 5 is a detail vertical section, showing 45 the arrangement of one of the supporting brackets 18 for one of the slide ways 16. Fig. 6 is a detail perspective of the foot-board in its erected position, showing the structure of the foot-board support. Fig. 7

50 is an enlarged detail perspective showing means for retaining the supporting arm 10 in the back.

In the drawing, similar reference characters refer to similar parts throughout the

several views, and the sectional views are 55 taken looking in the direction of the little arrows at the ends of the section lines.

Referring to the drawing, the chair frame consists of the rear posts 1 and front posts 2, which are extended to form the legs of the 60 chair. On the upper ends of the posts are arms 3. The posts are connected by suitable side frame pieces 4 and front and rear pieces 5 and 6, respectively. The frame is also provided with a horizontally-disposed 65 bottom piece 7, on which the adjusting mechanism for the adjustable back is mounted. This back consists of the side pieces 8 and cross pieces 9. The back is suitably pivoted, the pivots being such as are illustrated in my application for patent filed 70 March 29, 1909, Serial No. 486,470, and are not like illustrated.

The supporting arm 10 of the back is arranged vertically through the cross pieces, 75 as illustrated, and is provided with a link 11 on its lower end, which projects forwardly under the chair and is engaged by the adjusting rod 12. A return spring 13 for the back is provided. This adjusting 80 mechanism forms no part of my present invention, and I do not, therefore, illustrate and describe the same in further detail herein.

To retain the arm 10 in position in the 85 back I provide an angled clip 14, shown in detail in Fig. 7, which is slotted or notched to receive the rod, the rod being provided with a laterally-projecting pin 15, so that, by giving the rod a quarter turn, the pin 90 swings over and engages the clip. This provides a very simple and effective means for securing the arm.

The slide-ways 16 for the foot-rest slide bars 17 are formed of sheet metal, channel-shaped in cross section. These slide-ways are secured by their upper arms to the lower edges of the front and rear frame cross pieces 5 and 6. The slide ways are supported and braced by the brackets 18. 95 These brackets are in the shape of a double angle, the upper arm of the upper angle being secured to the inner sides of the frame pieces 4, and their lower angles being adapted to receive and support the slide-ways, as 100 clearly shown in Fig. 5. The sheet metal slide-ways are, by this means, effectively braced and supported. The brackets are

arranged at the front where the heavy strains occur when the foot-rest is extended.

The front cross piece 19 is mortised onto the ends of the slide bars, and, when the foot-rest is collapsed, slides between the front legs of the chair and under the front cross piece 5, forming, in appearance, a continuation of the same. The cross bars are provided with a rear cross piece 20 of metal, secured to their under edges and having an offset 21 therein to accommodate the link of the back adjusting means.

The foot-rest 22 is mounted on a bail-like support 23, the arms of the support being provided with laterally-turned journals 24, which are journaled in the slide bars, so that the foot-rest may be collapsed between the same, and, when erected, the support will rest upon the front cross piece 19. The arms of the support are provided with offset stops 25 for the foot-rest. The foot-rest is secured upon the horizontal portion of the support by means of the clips 26. A rack 27 for papers, books or other articles, is provided, the rack illustrated being basket-like in form, having side and rear walls but no front wall, so that the foot-board can collapse between the side bars above the rack. The rear wall of the rack is notched or cut away at 28, to accommodate the adjusting mechanism for the back. With this arrangement of the parts, I secure a foot-rest which is simple in structure, and, at the same time, is strong and rigid when extended. Further, it is easily operated and when collapsed, does not in any way injure the appearance of the chair.

I have illustrated and described my improvements in detail in one of the forms in which I have embodied the same, the form illustrated being the form at present preferred by me. I do not illustrate or describe the modifications herein, as I believe such modifications will be obvious to those skilled in the art to which this invention relates.

Having thus described my invention, what I claim as new and desire to secure by Letters Patent is:

1. In an adjustable chair, the combination with the frame comprising horizontally-disposed bottom, side, front and rear frame pieces; oppositely-facing channel-shaped slide ways secured by their upper arms to the lower edges of said front and rear frame

pieces; corner braces in said frame; double-angled brackets secured by the upper arms of their upper angles to said frame side pieces, the lower angles of said brackets being disposed beneath said slide ways and their intermediate parts being disposed beneath said braces; slide bars arranged in said ways; a foot-rest; and a bail-like support for said foot rest pivoted to said slide bars and disposed to rest on said front cross piece thereof when erected and to collapse onto a suitable support, the sides of said bail support being provided with offsets adapted to serve as stops for said foot-rest, said foot-rest being pivotally secured to the central portion of said bail, as described.

2. In an adjustable chair, the combination with the frame comprising horizontally-disposed bottom, side, front and rear frame pieces; oppositely-facing channel-shaped slide ways secured by their upper arms to the lower edges of said front and rear frame pieces; corner braces in said frame; double-angled brackets secured by the upper arms of their upper angles to said frame side pieces, the lower angles of said brackets being disposed beneath said slide ways and their intermediate parts being disposed beneath said braces; slide bars arranged in said ways; and a foot-rest carried by said bars and pivoted to collapse between said bars, as described.

3. In an adjustable chair, the combination with the frame comprising horizontally-disposed bottom, side, front and rear frame pieces; oppositely-facing channel-shaped slide ways secured beneath said frame; slide bars arranged in said ways; a foot-rest; and a bail-like support for said foot-rest pivoted to said slide bars and disposed to rest on said front cross piece thereof when erected and to collapse onto a suitable support, the side of said bail support being provided with offsets adapted to serve as stops for said foot-rest, said foot-rest being pivotally secured to the central portion of said bail, as described.

In witness whereof, I have hereunto set my hand and seal in the presence of two witnesses.

JERROLD F. WALTON. [L. S.]
